UNITED STATES PATENT OFFICE.

CHARLES E. COUGILL, OF KALAMAZOO, MICHIGAN, ASSIGNOR OF ONE-HALF TO ROSCOE M. TABOR, OF KALAMAZOO, MICHIGAN.

FURNACE.

1,214,279.

Specification of Letters Patent. Patented Jan. 30, 1917.

Application filed September 18, 1915. Serial No. 51,321.

To all whom it may concern:

Be it known that I, CHARLES E. COUGILL, a citizen of the United States, residing at Kalamazoo, Michigan, have invented certain new and useful Improvements in Furnaces, of which the following is a specification.

This invention relates to improvements in furnaces.

10 My improvements are particularly designed by me for embodiment and I have shown the same as I have embodied them in use in a furnace, such as is illustrated and described in the Strong Patent, No. 1,002,776, dated September 5, 1911. My improvements are, however, readily adapted for various designs of this type of furnace in which the air is circulated downwardly from a surrounding cold air chamber to an inner 20 hot air chamber.

The main object of my invention is to provide an improved furnace structure of the type described, in which the circulation from the surrounding cold air chamber is not materially affected or interfered with by the radiation of heat from the furnace body.

Further objects, and objects relating to structural details, will definitely appear from the detailed description to follow.

30 I accomplish the objects of my invention by the devices and means described in the following specification.

The invention is clearly defined and pointed out in the claims.

35 A structure which is a preferred embodiment of my invention is clearly illustrated in the accompanying drawings, forming a part of this specification, in which:

40 Figure I is a detail vertical section of a structure embodying the features of my invention. Fig. II is a horizontal section on a line corresponding to line 2-2 of Fig. I.

In the drawing similar reference numerals refer to similar parts throughout both views.

45 Referring to the drawings, 1 represents the furnace body, a portion of the fire-pot and the ash pit only being shown. I provide an outer casing 2 and an inner casing 3 spaced to provide a cold air supply chamber 4 between. The inner casing 3 is spaced from the body of the stove to provide a hot air chamber 5 between. The base ring 6 for the outer casing is secured to the stove body by the bars 7. The inner casing is supported 50 with its lower end in an elevated position by

means of the arms 8 which provide a space or passage 9 below the inner casing for the passage of air from the cold air chamber to the hot air chamber. To protect this passage space from heat radiated from the furnace body, which is found to interfere with the effective circulation from the cold air chamber to the hot air chamber I provide a baffle member or shield 10. This member 10 is mounted between the furnace body and the inner casing and in a spaced relation to both by means of the angle brackets 11 on the bars 7. The upper edge of this baffle member projects slightly above the lower edge of the inner casing, while the lower edge of the baffle member is supported in a slightly elevated position, so that it is possible for air to circulate under it and between it and the stove body. The baffle member thus arranged protects the space 9 from radiation from the furnace body and prevents the outer casing becoming heated by radiation and also prevents the air in the space 9 from becoming heated, so that circulation of air from the cold air chamber to the hot air chamber is not interfered with.

In the structure illustrated a front wall 12 is mounted on the furnace body and provided with outwardly projecting flanges 13 to which the outer casing is secured, the inner casing being secured to the rear side of the front wall. The ends of the baffle member are also secured to the front wall at 14.

The structure is very simple and economical and at the same time is found to be very efficient.

I have not attempted to illustrate or describe my improvements in the various adaptations or modifications which might be desirable to adapt them to different designs of furnaces, as I believe the disclosure made will enable those skilled in the art to which my invention relates to embody or adapt the same as structural conditions may render desirable.

Having thus described my invention, what I claim as new and desire to secure by Letters Patent, is:

1. In a furnace, the combination with the furnace body, of inner and outer casings spaced to provide a cold air chamber between, the inner casing being spaced from the furnace body to provide a hot air chamber between, the bottom of the inner casing being supported in an elevated position to 105

100

110

provide for the passage of air from the cold air chamber to the hot air chamber, a bottom ring for the outer casing, bars connecting the outer casing ring to the furnace body, supporting arms for said inner casing mounted on said bars, and a baffle member mounted on said bars in the said air passage space below said inner casing and in a spaced relation to both the inner casing and furnace body and with its lower edge in a slightly elevated position and its upper edge projecting slightly above the lower edge of said inner casing, and constituting a shield for said air passage space below the inner casing.

2. In a furnace, the combination with the furnace body, of inner and outer casings spaced to provide a cold air chamber between, the inner casing being spaced from the furnace body to provide a hot air cham-

ber, the bottom of the inner casing being supported in an elevated position to provide for the passage of air from the cold air chamber to the hot air chamber, and a baffle member, disposed in said air passage space below said inner casing and in a spaced relation to both the inner casing and furnace body and with its lower edge in a slightly elevated position and its upper edge projecting slightly above the lower edge of said inner casing and constituting a shield for said air passage space below the inner casing.

In witness whereof, I have hereunto set my hand and seal in the presence of two witnesses.

CHARLES E. COUGILL. [L. s.]
